UNITED STATES PATENT OFFICE.

JOHN C. BURRUSS, OF CARROLLTON, ILLINOIS.

LIFTING-JACK.

SPECIFICATION forming part of Letters Patent No. 270,012, dated January 2, 1883.

Application filed October 21, 1882. (No model.)

To all whom it may concern:

Be it known that I, JOHN C. BURRUSS, a citizen of the United States of America, residing at Carrollton, in the county of Greene and State of Illinois, have invented a certain new and useful Improvement in Lifting-Jacks, of which the following is a specification.

My invention relates to improvements in lifting-jacks; and it consists in the peculiar construction of the same, substantially as will be hereinafter more fully described.

In order to enable others skilled in the art to which my invention appertains to make and use the same, I will now proceed to describe its construction and operation, referring to the accompanying drawings, in which—

Figure 1 is a front elevation of my invention. Fig. 2 is a central vertical section of the same.

20 A represents a tube or shaft having a base, A', and upon its upper end a flange or collar, a, from which projects on one side a lug, a', and the other side is notched or recessed, d, as seen at a².

25 In the tube A, and projecting somewhat above it, is a loose bar, B, provided with a head, B'. On this bar B, just above the tube A, is a loose ring, C, having its central opening larger than the bar B and cut through it at an angle. This ring is on one side of its under face formed with a lug, c, which may be dropped into the recess a² in the flange a, in which case the ring will lie flat upon the tube or standard A and allow the bar B to rise and fall freely. If, however, the ring be raised and turned until the lug c rests upon the flange a, the ring will be held in this position at an angle to the rod or bar, and while allowing it to be lifted the edges of its central opening will bite upon the rod and prevent its being lowered.

40 D is a sash-head, also provided with a diagonal central opening larger than the rod or bar B, and under its rear side with two ears, d d, between which is pivoted the upper end of a lever, E. Just below this point this lever is pivoted between two links, D', which are secured at their lower ends to the lug a' of the flange a on the upper end of the tubular stand-

ard A. The head or casting D, being secured 50 to the links D' at one side of its center, has always a tendency to twist or set at an angle on the rod B.

When the jack is to be used the lever is raised to lower the head or clutch D until it 55 will go no farther, and the rod B drawn up with the other hand until it is of the proper height to engage with the object to be lifted. The lever now being depressed, the clutch D is twisted and grasps the rod B firmly. The 60 descent of the lever lifts the rod B, with the weight, against which it bears, and the upper ends of the links D' pass inward until they are upright, and the three pivot-points of the links and lever are directly over each other, 65 and the rod can be lifted no farther. When it is desired to lower the weight this action is simply reversed. If one stroke of the lever is not enough to lift the weight to the height required, the ring C is turned until its lug rests 70 upon the collar or flange a and takes the weight off the head D. The lever is then raised and the head slips down for a fresh grasp of the rod. To lower the jack in this position the ring C is turned until it falls to a horizontal 75 position, and the rod is lowered, as at first described, until the lever is raised to its highest point. Then use the ring C to hold the rod while the head D is raised to grasp the rod again in a higher place, and repeat this operation until the jack is lowered. The rod, being grasped by the twisting of the head D and ring C, is always held with a power proportioned to the weight resting on the jack.

Having thus fully described my invention, 85 what I claim as new, and desire to secure by Letters Patent, is—

1. In a lifting-jack, a lifting-head provided with a diagonal opening through which passes the lifting-rod, and connected at one side of its 90 center with an operating-lever, whereby the head slips easily down on the rod, but twists and tightly grasps it when being raised, substantially as and for the purpose set forth.

2. The locking-ring C, having a lug, c, in 95 combination with the standard A, provided with recess a² and an elevating-bar, B, substantially as and for the purpose set forth.

3. In a lifting-jack, the standard A, having lug a' , recess a^2 , and elevating-bar B, in combination with the locking-ring C, having a lug, c, and the lifting-head D, having a diagonal central opening, and pivoted at one side of its center to the lever E, connected by links D' to the standard A, substantially as and for the purpose set forth.

In testimony whereof I affix my signature in presence of two witnesses.

JOHN C. BURRUSS.
